UNITED STATES PATENT OFFICE

RALPH C. FEHELY AND RAYMOND F. STEVENSON, OF KENO, OREGON; SAID STEVENSON
ASSIGNOR TO SAID FEHELY

ORE CONCENTRATOR

Original application filed April 20, 1927, Serial No. 185,313. Divided and this application filed August 28, 1928. Serial No. 302,604.

This invention is a divisional part-of that for which on the 20th day of April 1927, we filed an application for Letters Patent in the United States, Serial Number 185,313 and 5 relates to the means for removing magnetic material from the bore bearing medium preliminary to the amalgamating process for separation of gold and silver.

For a full understanding of the invention 10 and the merits thereof, reference is to be had to the following description and the drawings hereto attached, in which:

Figure 1 is a top plan view of an ore separator embodying the invention.

15 Figure 2 is a side view of the apparatus.

Figure 3 is a vertical, central, longitudinal sectional view of the apparatus on the line 3—3 of Figure 1.

Figure 4 is an enlarged detail sectional 20 view on the line 4—4 of Figure 1.

Corresponding and like parts are referred to in the following description and designated in the several views of the drawings by like reference characters.

25 The numerals 1 and 2 designate pans, tables, or other like surfaces over which ore bearing material is caused to travel in placer mining. As shown, the pan 1 is disposed in a higher plane than the pan 2 and dis- 30 charges its contents into the latter. The level of the material in the pan 1 may be regulated by means of plugs 3, which close openings disposed at different elevations in the delivery end of the pan 1.

35 The sand, gravel, or other ore bearing medium is adapted to be supplied to the pan 1, by means of a flume not shown, or in any determinate way. A plurality of perforated pipes 4 extend over the bottom of the pan 1, and the perforations face upwardly, where- 40 by to deliver a plurality of jets in an up- ward direction across the path of the ore bearing medium and through the same to effect a loosening and an agitation thereof.

45 The pipes 4 are connected at one end to a supply pipe 5, located at one side of the pan or separating table.

A plurality of perforated pipes 6 extend over the bottom of the pan 2 and have the 50 perforations facing upwardly to throw the

jets across and through the material passing over the pan or separating surface. The perforated pipes 6 are connected at one end to a supply pipe 7. Other perforated pipes 8 are located above the bottom of the pan 2 and opposite the spaces formed between the perforated pipes 6. The perforations in the pipe 8 face downwardly, whereby to project the jets towards the separating surface, or in an opposite direction to the jets issuing 60 from the perforated pipes 6. The perforated pipes 8 are connected at one end to a supply pipe 9. The pipes 7 and 9 are located at the same side of the concentrator as the supply pipe 5 and the several pipes are connected with one another and with a source of supply not shown, of water, steam or air, under pressure, to insure formation of the jets in the manner and for the purpose stated.

A plurality of blocks 10 are placed upon 70 the bottom of the pan 2 forming the separating surface and are disposed between the perforated pipes 6 and in the plane thereof, as indicated most clearly in Figure 3. The blocks 10 have a plurality of pockets 11 75 formed in their upper surface for the reception of mercury, whereby to separate the precious metal from the ore by the well known process of amalgamation. As the sand, gravel, or other mineral bearing me- 80 dium passes over the separating surface 2 it is loosened and agitated by the upwardly projected jets issuing from the perforated pipes 6 and at the same time it is subjected to the downwardly projected jets issuing 85 from the perforated pipes 8, with the result that any precious metal, such as gold or silver, contained therein, is separated by amalgamating with the mercury contained in the cups 11. The cups or pockets 11 may be 90 formed in the blocks 10 in any manner, and in the preferable arrangement the blocks 10 consist of hard wood and the pockets 11 are formed by boring openings therein.

Magnetic material contained in the sand, or other medium is removed therefrom in its passage over the pan, or separating surface 1. For this purpose a plurality of electro- 95 magnets are arranged to travel over the pan 1 and are energized in their travel over the 100

pan to attract the magnetic material and become deenergized when clearing the pan to automatically discharge the magnetic material separated from the ore bearing medium.

5 The electromagnets include soft iron bars 13 which radiate from a hub 14 formed of non-magnetic conductive material, such as brass, and upon the inner ends of the bars are mounted helices or coils 15, through which an electric current is caused to circulate to effect magnetization of the cores or bars 13 in a manner well understood. This magnetic separator is mounted upon the upper end of a shaft 16 to which rotary movement 10 is imparted from a suitable source by means of a shaft 17 and gearing 18. One terminal of each of the coils 15 is connected to a brush 19 and the other terminal is connected to the hub 14 or other suitable conductor. The numeral 20 designates a segment-contact with 15 which the brushes 19 successively engage. One lead from a suitable source of current supply is connected to the segment contact 20 and the other lead is connected to the hub 20 14 or like part, as indicated most clearly 25 in Figure 4. A brush 21 frictionally engages the hub 14 or like part, thereby admitting of rotation of the magnetic separator.

In the operation of the separator the electromagnets pass over the table 1 and attract 30 the magnetic material from the ore bearing medium. The electromagnets are successively energized by the closing of the circuit through their coils 15. This takes place when 35 the electromagnets reach a position just prior to their passage over the separating pan or table.

The electromagnets remain energized during 40 their travel over the separating pan or table, and after clearing the same the current is broken and the electromagnets become de-energized and drop the load previously attracted. So long as the brushes 19 engage the contact 20 the circuit is closed through cer- 45 tain coils 15, with the result that the cores or bars 13 are magnetized. This takes place when the electromagnets are passing over the separating pan or table 1, and after clearing the same the brushes 19 clear the contact 20, 50 thereby breaking the circuit, with the result that the electromagnets become deenergized and discharge the material attracted thereby.

Having thus described the invention, we claim:

55 1. The combination with an approximately horizontal separating tank open at its top, of a rotary magnetic separator comprising a hub rotatably mounted at one side of said tank, soft iron bars radiating from the hub to sweep 60 across the open upper end of said tank as the hub rotates, coils about the inner end portions of the bars, means for energizing the coils during movement of the bars over the separating tank, and means at the bottom of 65 the tank for directing jets upwardly therein

to agitate contents of the tank and project particles of metal upwardly into position to be attached by the magnetized bars and adhere to all surfaces of the bars.

2. The combination with an approximately 70 horizontal separating tank open at its top and free from obstructions thereabove, of a magnetic separator comprising a plurality of electric magnets radiating from an axis disposed vertically at one side of the tank and adapted 75 to sweep across the open upper end of the tank and remove particles from the ore amenable to magnetic influence, and means for agitating contents of the tank and projecting the said particles upwardly into position to be 80 attracted by said magnets and adhere to the same.

In testimony whereof we affix our signatures.

RALPH C. FEHELY.
